UNITED STATES PATENT OFFICE.

OLAF W. PETERSEN, OF BUFFALO, NEW YORK, ASSIGNOR TO PETERSEN STOKER COMPANY, OF BUFFALO, NEW YORK.

GRATE.

Application filed September 28, 1921. Serial No. 503,880.

To all whom it may concern:

Be it known that I, OLAF W. PETERSEN, a citizen of the United States, residing at Buffalo, in the county of Erie and State of New York, have invented a new and useful Improvement in Grates, of which the following is a specification.

This invention relates to grates of the kind in which the fuel while being burned is advanced along the grate, and more particularly to grates of this kind in which the grate-bars can be rotated to advance the fire.

The objects of the invention are to provide grates of this kind with grate-bars having plates of improved construction for advancing the fire; also to provide means of improved construction for rotating the grate-bars; also to provide means of improved construction for securing the rotary grate-bars in correct operative relation to the grate; also to so construct the grate that the parts thereof which are subjected to the heat of the fire can be easily removed from the grate and replaced by corresponding new parts; also to so construct grates of this kind as to avoid the loss of unburned fuel; also to improve the construction of grates of this kind in other respects hereinafter specified.

In the accompanying drawings:

Fig. 1 is a fragmentary sectional plan view of a furnace provided with a grate embodying the invention.

Fig. 2 is a longitudinal sectional elevation of the furnace, showing the grate in elevation.

Fig. 3 is a longitudinal sectional elevation thereof on line 3-3, Fig. 1.

Fig. 4 is a fragmentary longitudinal sectional elevation of the grate, showing the parts of the grate in different positions.

Fig. 5 is a transverse sectional elevation thereof on line 5-5, Fig. 2.

Fig. 6 is a fragmentary transverse sectional elevation thereof on line 6-6, Fig. 3.

Fig. 7 is a fragmentary perspective view of the front finger supporting bar of the grate, and one of the fingers.

Fig. 8 is a fragmentary perspective view showing the rear finger supporting bar ready to be positioned in one of the supporting side members of the grate, and one of the fingers.

Fig. 9 is a fragmentary perspective view of one of the supporting side members of

the grate with the locking devices ready to be placed into their operative relations thereto.

Figs. 10 and 11 are fragmentary sectional plan views thereof on lines 10-10 and 11-11 respectively, Fig. 2.

Fig. 12 is a perspective view of a locking or retaining member for holding the grate-bars in operative relation to a supporting side member of the grate.

Fig. 13 is a side elevation on an enlarged scale, showing two of the fire-supporting bars of the grate in operative relation to each other.

Fig. 14 is a similar view showing the two plates in a position to advance the fire.

Fig. 15 is a sectional elevation of one of the plates on line 15-15, Fig. 13.

The grate may be used in connection with a furnace of any suitable construction, that shown including a front wall A having a suitable opening through which the fuel may be admitted to the furnace, a side wall a and a rear wall a'.

The parts of the grate are mounted on and supported by a plurality of supporting side members B which extend lengthwise of the furnace and the ends of which are suitably supported on the front and rear walls of the furnace. Any number of these longitudinal supporting members may be employed, depending upon the width of the grate, and the grate-bars are supported at their opposite ends in these longitudinal members.

The fuel and fire are carried lengthwise of the grate by means of a plurality of rotatable grate-bars, each of which includes a central rod or shaft and a plurality of plates supported on the shaft and arranged so that the fire will rest on the upper edges of the plates. C represents the rotary shafts of the grate-bars, the intermediate portions of which are adapted to receive the plates and hold the same against turning. In the construction shown for this purpose, the intermediate portions are square in cross section and the end or bearing portions e are of circular cross section. The intermediate, square portions of the rods or shafts are adapted to support the plates D upon which the fire rests. These plates are polygonal in their form, being square in the construction illustrated, and are spaced apart and so arranged that the plates of one grate-bar enter into the spaces between the plates of an ad-

65

5 jacent grate-bar. In order to properly space the plates on the shafts, each of the plates is preferably provided with spacing collars or projections d which extend outwardly from one side of the plate and are adapted to engage the adjacent side of the next plate. These spacing collars are so arranged as to extend into proximity to the corners of the plates when the plates are in the position shown in Figs. 4 and 14. The object of these collars is to retard the falling of the fuel between the plates while the plates are being turned for the purpose of advancing the fuel.

15 Each plate is also provided with inwardly-extending parts d' having flange portions d'' at the inner faces thereof. The flanges d'' are adapted to engage the corners or edge portions of the shaft or rod C. The inwardly-extending portions d' are preferably separated by slots or spaces d^3 so that the plates engage on the corner or edge portions of the supporting shafts, thereby eliminating as much machining and fitting of the parts as possible.

20

25

It has been found that in the use of grates of this kind, particles of fuel sometimes become wedged between the plates and thus interfere with the operation of the grate. In order to overcome this difficulty one face of each plate in the particular construction shown, is concaved or dished as indicated at d^4 in Figs. 13 to 15, thereby forming plates which have peripheral portions of greater thickness than their intermediate portions. This eliminates the wedging of the particles.

This eliminates the wedging of the particles of fuel between adjacent plates, since if a piece of material is sufficiently small to pass into the space between the edge portions of the plates, it will drop freely past the intermediate portions thereof. Only one of the faces of the plates is shown dished but it will be obvious that if desired, both faces of the plates can be formed in this manner.

45 By means of the construction of the plates described, all of the plates of the grate may be made the same and the plates on opposite grate bars are arranged to face in opposite directions, thereby producing a staggered arrangement of plates which enables the plates of one grate-bar to enter into the spaces between the plates of an adjacent grate-bar.

50

It is desirable to have the plates normally arranged with their upper faces substantially in alinement or in the same plane and thereby avoid having the corners of the plates project into the fire, which would cause the burning of the corners. For this purpose the grate-bars are rotated intermittently by means of pawl and ratchet mechanisms which are preferably constricted as follows:

65 which are preferably constructed as follows. Each shaft C is provided at one end with a ratchet wheel E suitably secured thereon and having a number of teeth corresponding to the number of sides of the plates D, four

teeth being shown in the construction illustrated, in which square plates are employed. These ratchet wheels are adapted to be turned by means of pawls F having enlarged head portions f provided with openings f' , 70 within which the ratchet wheels E are arranged. The head of each pawl F is provided with a tooth f^2 extending inwardly into the opening in the head and adapted to engage with the teeth of the ratchet wheels. 75 The pawls hang on the ratchet wheels and when the same are moved into the position shown in Fig. 3, the tooth portion of each pawl drops by gravity into engagement with a tooth of the ratchet wheel. 80

In order to actuate all of the grate-bars at the same time, the pawls F are connected at their lower ends to a connecting bar G by means of a plurality of pins or bolts g passing through slots g' in the lower ends of the pawls F. The slots g' permit each of the pawls to drop into engagement with a tooth of a ratchet wheel independently of other pawls. The connecting bar G may be swung back and forth to turn the grate-bars by any suitable means, such for example, as a lever H pivoted at h in front of the furnace and connected by means of a link h' with the connecting bar G. When the lever H is swung from one end of its path of movement to the other end, the grate bars are turned through a quarter of a revolution and the plates D are all moved into positions in which the upper faces thereof lie substantially in the same plane. During this movement the corners of the plates engage the fire and feed the same toward the rear of the furnace.

At the front and rear of the grate, fingers I and K are arranged in such a manner as to extend between the plates of the adjacent grate-bars. These fingers are stationary and serve to support the fire before it passes to the rotary grate bars and after it leaves the same. The fingers may

the plates of an adjacent grate-bar. The body portions of the fingers also protect the supporting bar against the fire, so that only the fingers which can be readily removed and replaced, are subject to the destructive action of the fire. The rear fingers K, Figs. 3 and 8, are substantially of the same construction, and are supported on a rear finger-supporting bar k, the ends of which rest in slots k' formed in the side supporting members B. The fingers are provided with enlarged portions k² having slots k³ which enable the fingers to straddle the finger bar k. The foremost, rotary grate-bar takes the fuel from the front fingers I and the rear grate-bar discharges the remaining portions of the fire to the rear fingers k. The construction of the front and rear fingers and finger bars prevents the warping or otherwise injuring of the supporting bars.

From the fingers K the ashes or clinkers remaining in the fire are discharged upon a dumping grate or support L, which, in the construction shown, consists of a plurality of links or sections l, each of which is connected at one end by a shaft or rod l' which is pivoted on the side supporting members B of the grate. The links or sections l are connected at their other ends to a rod of shaft l² and each of the links is provided with enlarged end portions or lugs which serve to space the intermediate portions of the links apart. The dumping grate L also has a pair of sections l³ provided with a downwardly projecting portion l⁴ which is pivotally connected to a rod or link l⁵ extending through the front wall of the furnace and which is provided with notches l⁶ adapted to engage with a holding projection l⁷ to hold the pivoted grate member either in the position shown in full lines in Fig. 3 or in the dotted line position. By means of this grate any clinkers or unburned matter carried to the rear of the furnace may be discharged into the ash pit.

In order to rotatably hold the grate-bars in operative relation to the supporting side members B, the construction shown in detail in Figs. 9-12 is preferably, though not necessarily employed. In this construction the cylindrical end portions c of the shafts of the grate-bars are journalled in bearings formed by semi-circular depressions m in the supporting side members B and by corresponding depressions in key members M. These key members are held in place on the supporting side members B by means of upwardly extending projections N on these side members, which have reduced neck portions n provided with tapering or inclined faces n' and enlarged head portions n², preferably provided with inclined faces n³ on their opposite sides. Each key member M is

provided with correspondingly inclined faces m' which are adapted to engage with the faces n' of the projections N. The key member M is also provided with an upwardly extending part m² which enters between the head portions n². The head portions n² hold the key member M against movement upwardly and means of any suitable construction are preferably provided for holding this key member against moving laterally out of its operative position. For this purpose a retaining member O is shown in the construction illustrated, which is adapted to interlock with the heads n² and to engage a key member M and to hold the same against moving laterally out of its operative position. The retaining member shown is provided with a head portion o adapted to rest on the upper faces of the projections N of the supporting side members and a dovetail portion o' is adapted to engage the inclined faces n³ of the projecting members N. The retaining member also has a downwardly extending portion o² provided with a semi-circular depression o³ for the shaft of a grate-bar. The downwardly projection portion o² engages the side of the key member M and holds the same against movement laterally out of its operative position.

It is also desirable to provide means for protecting the ratchet members of the grate bars from the fire and from ashes or cinders dropping from the fire, and for this purpose a protecting portion is preferably formed integrally with each retaining member O. In the construction shown for this purpose in Figs. 9, 10 and 11, the upper portion o of the retaining member is extended laterally and provided at its inner face with a downwardly extending flange P which extends substantially parallel to the inner face of the ratchet and ratchet wheel. The top portions o and the side portions P of the retaining members O prevent injury to the ratchet mechanism of the grate-bars, due to the heat of the fire and to cinders or ashes dropping from the fire. The retaining member shown in Fig. 12 is not provided with the inner, side wall P and this member is intended to be used in connection with those bearings of the grate-bars which are not provided with ratchets and ratchet wheels.

The grate-bar described can be readily manufactured, since the parts thereof can be made of cast metal and require very little machining. The grate has the advantage of occupying very little space in the furnace and at the same time effectively passing a fire from the front to the rear of the furnace. In case any part of the grate becomes injured, it is a very simple matter to remove the injured part and replace the same by a new part. The plates of the grate-

bars are loosely held on the shafts C and the shafts themselves are readily removed from the supporting side members. The front and rear fingers I and K can be removed by simply raising them out of engagement with their supporting bars, and the links or parts 7 of the rear, pivoted grate member are also loosely mounted on their supporting shafts. The grate, however, is very reliable in its action and the plates of the grate-bar are not easily burned for the reason that the surfaces thereof supporting the fire do not become excessively heated, since three of the four surfaces of each plate are being cooled while the fourth surface supports the fire.

The rotary grate-bars receive the fresh fuel at the front of the grate and the fire is gradually fed to the rear of the grate. The smoke and gas given off by the green fuel at the front of the grate pass over the hot fire at the intermediate and rear portions of the grate and are consumed, producing practically smokeless combustion. Any fuel not consumed while on the rotary grate bars is discharged to the rear finger bars and to the dumping grate, which being stationary, retard the movement of the fuel so as to ensure the complete combustion of all of the fuel. This retarding action has the important effect of ensuring a complete combustion of the fuel and automatically prevents the discharge of unconsumed fuel from the grate. The rear finger bars and the dumping grate preferably slope downwardly as shown in Figs. 2 and 3, so as not to retard the movement of the fire to an excessive extent, but the angle of the fuel retarding portion of the grate may be varied, if desired.

I claim as my invention:—

1. In a grate, the combination of a plurality of rotary grate-bars each including a shaft and plates arranged thereon, the plates of one grate-bar entering into spaces between plates of an adjacent grate bar, and collars on said plates extending into the spaces between said plates for spacing said plates relatively to each other, said collars extending into proximity to the peripheries of the plates of an adjacent grate-bar to prevent large particles of fuel from falling through the spaces between plates.

2. In a grate, the combination of a plurality of rotary grate-bars each including a shaft and polygonal plates arranged at intervals thereon to support the fire on the edges of said plates, the plates for one grate-bar entering into the spaces between plates of an adjacent grate-bar, and laterally extending collars on each of said plates extending into the spaces between plates, said collars being spaced from the shaft engaging portions of said plates and extending into close proximity to the corners of the plates of an adjacent bar when said grates are rotated to limit the fall of fuel through said spaces.

3. In a grate, the combination of a plurality of rotary grate-bars each including a shaft and polygonal plates arranged at intervals thereon to support the fire on the edges of said plates, the plates of one grate-bar entering into the spaces between plates of an adjacent grate-bar, the outer edges of said plates being of greater thickness than the inner portions thereof.

4. In a grate, the combination of a plurality of rotary grate-bars each including a shaft and polygonal plates arranged at intervals thereon to support the fire on the edges of said plates, the plates of one grate-bar entering into the spaces between plates of an adjacent grate-bar, a face of each of said plates being dished to prevent the accumulation of fuel and ash in the spaces between the plates.

5. In a grate, the combination of a plurality of rotary grate-bars each having a shaft and plates mounted on said shaft to support the fire on the edge portions of said plates, a ratchet wheel secured on each shaft, a ratchet arm adapted to engage with said ratchet wheel and having an enlarged head provided with an opening in which said ratchet wheel is arranged, and a tooth extending inwardly into said opening and adapted to cooperate with said ratchet wheel.

6. In a grate, the combination of a plurality of rotary grate-bars each having a shaft and plates mounted on said shaft to support the fire on the edge portions of said plates, a ratchet wheel secured on each shaft, a ratchet arm adapted to engage with said ratchet wheel and having an enlarged head provided with an opening in which said ratchet wheel is arranged, a tooth extending inwardly into said opening and adapted to cooperate with said ratchet wheel, and a connecting bar to which all of said ratchet arms are pivotally connected and which swings said arms to cause an intermittent rotation of said shafts.

7. In a grate, the combination of a plurality of rotary grate-bars each having a shaft and plates mounted on said shaft to support the fire on the edge portions of said plates, a ratchet wheel secured on each shaft, a ratchet arm adapted to engage with said ratchet wheel and having an enlarged head provided with an opening in which said ratchet wheel is arranged, a tooth extending inwardly into said opening and adapted to cooperate with said ratchet wheel, a connecting bar, and a slideable and pivotal connection between each of said ratchet arms and said bar, whereby each of said ratchet arms is adapted to engage said ratchet wheels independently of each other and whereby said

bar is adapted to swing said arms to rotate all of said grate-bars.

8. In a grate, the combination of a plurality of rotary grate-bars each having a shaft and plates mounted on said shaft to support the fire, and spaced apart, a series of stationary fingers arranged at an end of said grate and adapted to enter into the spaces between adjacent plates of the grate 5 bar nearest to said end and having bifurcated end portions, and a finger-supporting bar arranged in operative relation to said grate and which said bifurcated parts of said fingers are adapted to straddle, where- 10 by the fingers are removably held on said finger-supporting bar.

9. In a grate, the combination of a plurality of grate-bars each having a shaft and plates mounted on said shaft to support the 20 fire, and spaced apart, stationary fingers adapted to enter into the spaces between adjacent plates and having body portions which are of greater width than the portions thereof which extend into the spaces 25 between said plates, said body portions being bifurcated, and a finger-supporting bar arranged in operative relation to said grate and which said bifurcated parts of the fingers straddle, said body portions spacing 30 said fingers relatively to each other and protecting said supporting bar from the action of the fire.

10. In a grate, the combination of a rotary grate bar, a side supporting member 25 on which said rotary grate-bar is journalled, a key having a part which engages said grate-bar to hold the same in place on said supporting member, said key being adapted to interlock with a portion of said support- 40 ing member to hold the key against vertical movement relatively to said supporting member, and apart movable vertically into engagement with said supporting member and adapted to hold said key against lat- 45 eral movement.

11. In a grate, the combination of a rotary grate-bar, a side supporting member having a part forming a journal for said grate-bar, upwardly extending projections 50 on said supporting member arranged at opposite sides of said journal portions, a key member having a part adapted to cooperate with said journal portion to rotatably confine said grate-bar in operative relation to 55 said supporting member, and held against vertical movement by said projections, and a part engaging said projections and confining said key member against sidewise movement.

12. In a grate, the combination of a rotary grate-bar, a side supporting member having a part forming a journal for said 60 grate-bars, upwardly extending projections on said supporting member arranged at op- 65 posite sides of said journal portions and

having reduced neck portions and enlarged head portions, a key member adapted to engage said shaft and said projection and held against upward movement by the head portions of said projection, and a part engag- 70 ing said key member and holding the same against lateral movement and having a part interlocking with said head portions and held against lateral movement thereby.

13. In a grate, the combination of a rotary 75 grate-bar, a side supporting member having a part forming a journal for said grate bars, upwardly extending projections on said sup- 80 porting member arranged at opposite sides of said journal portions and having reduced neck portions and enlarged head portions, a key member adapted to engage said shaft and said projection and held against upward movement by the head portions of said projection, and a key holding member move- 85 able vertically into and out of engagement with said head portions and having a dove-tailed connection therewith, and engaging said key portion, said dovetailed connection holding said key holding member and said key against lateral movement.

14. In a grate, the combination of a ro- 90 tary grate-bar, means engaging said grate- 95 bar for turning the same, a side supporting member on which said grate-bar is jour- 100 nalled, a key having a part engaging said grate-bar to hold the same in place and en- 105 gaging said supporting member and inter- locking therewith to hold said key against vertical movement relatively to said sup- 110 porting member a part loosely engaging said supporting member and held against lateral movement thereby, said part engaging said key and holding said key against lateral movement, and a portion of said vertically movable part which overhangs said turning means for protecting the same against injury from the fire.

15. In a grate, the combination of a plu- 110 rality of rotary grate bars adapted to ad- 115 vance the fuel from the receiving end of the grate to the discharge end thereof in a substantially horizontal direction, and a rel- atively stationary downwardly inclined fuel-retarding grate portion arranged at the discharge end of said rotary grate bars, and on which the combustion of the fuel is completed.

16. In a grate, the combination of a plu- 120 rality of rotary grate bars adapted to ad- 125 vance the fuel from the receiving end of the grate to the discharge end thereof, and a relatively stationary fuel-retarding grate portion arranged at the discharge end of said rotary grate, and sloping downwardly therefrom and on which the combustion of the fuel is completed.

17. In a grate, the combination of a plu- 130 rality of rotary grate-bars adapted to ad- vance the fuel from the receiving end of the

grate to the discharge end thereof, and a relatively stationary fuel-retarding grate portion arranged at the discharge end of said rotary grate bars and including finger bars cooperating with said rotary grate-bars to receive the fuel therefrom, and a grate member arranged in rear of said finger bars, the final combustion of the fuel taking place on said finger bars and rear grate member.

10 18. In a grate, the combination of a plurality of rotary grate-bars adapted to ad-

vance the fuel from the receiving end of the grate to the discharge end thereof, and a relatively stationary fuel-retarding grate portion arranged at the discharge end of 15 said rotary grate bars and including finger bars cooperating with said rotary grate-bars to receive the fuel therefrom, and a dumping grate member arranged in rear of said finger bars.

OLAF W. PETERSEN.
